SELECTIVE SPEED DRIVE

John B. Brennen, Atlanta, Ga.

Application December 11, 1934, Serial No. 757,061

6 Claims. (Cl. 74—217)

Generically this invention relates to drives for machinery, but it is more especially directed to a selective or variable speed drive for use in connection with cotton distributors and feed controls.

Heretofore, it has been necessary to either stop the flow of cotton through the cleaning machines entirely as the distributors or hoppers become filled and to then start the flow again as the hoppers call for cotton or when the relay on the distributor control has completed its time cycle. Therefore one of the principal objects of this invention is the provision of a selective or variable speed drive device, especially applicable to my Patent No. 1,899,791, Feb. 28, 1933, adapted to reduce and increase the speed of bale breakers or hoppers used in feeding cotton cleaning machines delivering to distributors and pickers, to produce a more even and continuous flow of the cotton through the cleaning machines and prevent said machines running idle every time the start-stop control operates.

An important object of this invention is the provision of a selective or variable speed drive for cotton cleaning machines and the like including means for intermittently varying the driving speed of the device in accordance with operating requirements.

A further important object of this invention is the provision of a selective or variable speed drive comprising a series of belt driven pulleys, certain of said pulleys being connected to and adapted to drive a driven member at one speed, and certain others similarly adapted to drive said driven member at a different speed, a belt connecting a prime mover with a respective pulley, and means for automatically shifting said belt from one pulley to another to vary the speed of the driven member in accordance with operating requirements.

In describing my invention in detail, reference will be had to the accompanying drawing, wherein like characters denote like or corresponding parts throughout the several views, and in which:

Fig. 1 is a plan view of my improved selective speed drive.

Fig. 2 is a cross sectional view on the line 2—2 of Fig. 1.

Fig. 3 is a fragmentary plan view looking in the direction of the arrows line 3—3 of Fig. 2.

In connection with cotton cleaning machines, distributors and the like, wherein the overflow or operation of certain components of the apparatus or load in transit, through the instrumentality of start-stop control devices effects the complete respective stopping and operation of the

machines for definite time periods, certain disadvantages are presented, such as permitting some of the components to at times carry too much load and others to run idle, and it was to overcome such disadvantages, and to provide a selective speed drive comprising a pulley and belt unit including a driving pulley for driving a driven member at one speed and a similar unit for driving said driven member at a different speed, a belt connecting a prime mover with a respective driving pulley, and means for automatically shifting the prime mover belt from the driving pulley of one unit to that of the other unit to intermittently vary the speed of the driven member in accordance with operating requirements and to insure an even flow of the cotton through the machine, that I designed the differential drive forming the subject matter of this invention.

In the illustrated embodiment characterizing this invention there is shown a main driving shaft 1 and mounted on said shaft and suitably secured thereto is a wide pulley 2, which pulley or unit, for purposes of description, may be referred to as a prime mover unit A.

The frame B may be suitably supported as a hanger or otherwise as desired and comprises parallel end members or bars 3 and 4 and spaced inwardly therefrom are the parallel bars 5 and 6, the free ends of which extend beyond the ends of said bars 3 and 4. The opposite ends of the respective bars are connected to a cross bar 7 by rivets 8 or other suitable fastening means. Mounted on bar 3 adjacent its free end is a bearing 9 secured by bolts 10, and in alignment therewith similarly mounted on bar 5 is bearing 11. Similar and aligned bearings 12 and 13 are mounted on bars 4 and 6, respectively.

A shaft 14 is journaled in bearings 9 and 11 and mounted on its inner end is drive pulley 15 secured by set screws 16, or keyed as desired. Similarly journaled in bearings 12 and 13 and in meeting alignment with shaft 15 is a shaft 17 on which is mounted pulley 18 similar to pulley 15, and on the free end of said shaft 17 intermediate pulleys 15 and 18 is suitably mounted a loose or idler pulley 19. Suitably mounted on shaft 14 adjacent to bearing 9 is pulley 20 and similarly mounted on shaft 17 adjacent bearing 12 is pulley 21 for a purpose directly more fully appearing.

It will be noted that the three pulleys 15—19—18 combined are the same width as pulley 2 to which they are connected by prime mover belt 22 shown applied to and in driving position with respect to pulley 18, but which is adapted to be shifted across loose pulley 19 and to pulley 15.

by the pilot motor and associated screw and shifting mechanism C, which will now be described.

The motor and shifting mechanism C comprises pilot motor 23 suitably mounted on cross bar 24 supported on the free ends of frame members 5 and 6. Said motor 23 includes drive gear 25 adapted to mesh with gear 26 fixedly secured on one end of screw 27 journaled in suitable bearings 28 carried by bars 5 and 6. Mounted on screw 27 is a follower 29 to which is suitably connected the substantially U-shaped or loop belt shifter member 30 through which is adapted to extend belt 22 and by means of which said belt is 10 intermittently shifted to and from drive pulleys 15 and 18. In order to maintain shift member 30 properly positioned and out of contact with pulleys 15-19-18, follower 29 is adapted to engage the stationary slide member 31 suitably supported 15 on said frame members 5 and 6.

The pilot motor 23 is connected to a source of power not shown, and controlled by a reversing switch, not shown, suitably controlled to operate said belt shifter in accordance with operating requirements.

While I have preferably shown a pilot motor and screw means for shifting the prime mover belt, it is to be understood that a manually operated thruster or shifting means may be employed 30 if desired.

Positioned with respect to frame B in accordance with the particular requirements, is a suitably mounted countershaft 32 on which is mounted and secured, what may be termed, the normal or fast speed pulley 33 in alignment with pulley 21 to which it is connected by belt 34. Mounted on said shaft 32 in alignment with pulley 20 is slow speed pulley 35 connected with pulley 20 by belt 36. Pulley 35 is of larger diameter than pulley 33 and therefore is designed to drive shaft 32 at a slower speed than pulley 33, as will be well understood. Also mounted on shaft 32 intermediate the pulleys 33 and 35 is pulley 37. This pulley may however be mounted at any desired point on shaft 32. Pulley 37 is adapted to drive the feed hopper or bale opener mechanism D, which for purposes of description may be termed the driven member.

The feed hopper or bale opener D comprises shaft 38 suitably journaled in bearing 39, and on the free end of which is suitably mounted and secured pulley 40 which is connected to pulley 37 by belt 41.

Although the operation of the device would seem to be clear from the above description it 55 might be well to further state as follows:

When power is delivered from pulley 2 or prime mover A through belt 22 to drive pulley 18, power will be transmitted to pulley 21, pulley 33, pulley 37, pulley 40 and operate the driven member D at normal speed, and when operating conditions necessitate changing the speed or when a definite time period has elapsed, pilot motor 23 will be started and will operate screw 27 and shifter 30 60 to shift belt 22 across loose pulley 19 to pulley 15, and power will then be transmitted through pulley 15, and pulleys 20, 35, 37, and 40 to operate drive element D at a slower speed and for the requisite time period as above referred to, at which time 65 the reversing switch or other control means will cause the motor to reverse the operation of screw 27 and direction of travel of follower 29 and shift member 30, to shift belt 22 across loose pulley 19 and into operative engagement with pulley 18 as 70 in the first instance.

It will be noted that a wide speed range in pulley 38 can be obtained by changing the sizes of pulleys 33 and 35. It will likewise be observed that when the device is in operation the respective drive units are in continuous operation, 5 whether driving the driven member or running idle, thereby eliminating the disadvantages incident to the sudden starting and stopping of parts, thereby not only effecting a smooth running efficient mechanism, but increasing the life of the 10 device.

From the above it will be apparent that I have designed a selective speed drive of the character described, comprising few parts, expeditiously operable to vary the speed of the driven member, 15 simple in construction, versatile in use, and efficient for the purposes intended.

I have described the preferable form of my invention although, I desire to emphasize that various minor changes in details of construction, proportion and arrangement of parts, may be resorted to within the scope of the appended claims without departing from or sacrificing any of the principles of this invention.

Having thus described my invention, what I 25 desire protected by Letters Patent is as set forth in the following claims:

1. A selective speed drive of the character described comprising a pair of independently rotatably aligned shafts, a trio of pulleys, the outermost pulleys of the trio being connected to the inner extremities of the aligned shafts, the intermediate pulley being independently rotatable with respect to said shafts, a driven shaft, a pulley keyed to the driven shaft, and means connecting the free ends of the aligned shafts with the driving shaft, whereby the last-mentioned pulley may be operated at different speeds.

2. A selective speed drive of the character described comprising a pair of independently rotatably aligned shafts, a trio of pulleys, the outermost pulleys of the trio being connected to the inner extremities of the aligned shafts, the intermediate pulley being independently rotatable with respect to said shafts, driving pulleys mounted on the free ends of said shafts, a driven shaft, a pulley keyed to the driven shaft, driving means interconnecting the driving pulleys and driven shaft, the respective driving means adapted to drive said pulley at different speeds.

3. A selective speed drive of the character described comprising a pair of independently rotatably aligned shafts, a trio of pulleys, the outermost pulleys of the trio being connected to the inner extremities of the aligned shafts, the intermediate pulley being independently rotatable with respect to said shafts, a driven shaft, a pulley connected to the driven shaft and means connecting the free ends of the aligned shafts with the driven shaft to drive said pulley at 60 different speeds, driving means respectively engageable with the pulleys of said trio and shiftable from one outermost pulley to the other whereby intermittent rotation of said driven pulley may be effected.

4. A selective speed drive of the character described comprising a pair of independently rotatably aligned shafts adapted to rotate at the same speed, a trio of pulleys, the outermost pulleys of the trio being connected to the inner ends 70 of said shafts, the intermediate pulley being independently rotatable with respect to said shafts, a driven shaft, a pulley secured to the driven shaft, and means connecting the free ends of the aligned shafts with the driven shaft for driving 75

said shaft at different speeds, belt means adapted to engage any one of the respective pulleys of said trio, and means for reversibly shifting said belt from one outermost pulley to the other, whereby power delivered to the driven pulley may be intermittently cut off and alternately applied at different driving speeds.

5. A selective speed drive of the character described comprising a pair of independently rotatably aligned shafts adapted to rotate at the same speed, a trio of pulleys, the outermost pulleys of the trio being connected to the inner ends of said shafts, the intermediate pulley being independently rotatable with respect to said 10 shafts, a driven shaft, a pulley secured to the driven shaft, and means connecting the free ends of the aligned shafts with the driven shaft for driving said shaft at different speeds, a prime mover, a belt adapted to connect said prime

5
mover with any one of the respective pulleys of said trio, and means for reversibly shifting said belt from one outermost pulley to the other whereby power delivered to the driven pulley may be intermittently cut off and alternately applied at different driving speeds.

6. A selective speed drive of the character described comprising a pair of independently rotatably aligned shafts, a trio of pulleys, the outermost pulleys of the trio being connected to the inner extremities of the aligned shafts, the intermediate pulley being independently rotatable with respect to said shafts, driving pulleys mounted on the free ends of said shafts, a driven shaft, pulleys of different dimensions removably mounted on the driven shaft and connected to said driving pulleys so as to impart different driving speeds to said driven shaft.
